(57) **CLAIM**

The ornamental design for a blank for a bicycle box, as shown and described.

DESCRIPTION

FIG. 1 is a right side perspective view of the present invention;

FIG. 2 is a left side perspective view of the present invention;

FIG. 3 is a right side elevational view of the present invention;

FIG. 4 is a left side elevational view of the present invention;

FIG. 5 is a front elevational view of the present invention;

FIG. 6 is a rear elevational view of the present invention;

FIG. 7 is a top plan view of the present invention; and,

FIG. 8 is a bottom plan view of the present invention.

The dashed lines in the drawings depict fold lines of the

blank for a bicycle box and form part of the claimed design.
